(57) **CLAIM**

The ornamental design for a safety selector for AR15 pattern firearms, as shown and described.

DESCRIPTION

FIG. 1 is a perspective view of a safety selector for AR15 pattern firearms according to a first embodiment of the present design;

FIG. 2 is a 180 degree rotated perspective view of FIG. 1; FIG. 3 is a rear plan view of the design shown in FIG. 1; FIG. 4 is front plan view of the design shown in FIG. 1; FIG. 5 is a right side view of the design shown in FIG. 1; FIG. 6 is a left side view of the design shown in FIG. 1; FIG. 7 is a top view of the design shown in FIG. 1; FIG. 8 is a bottom view of the design shown in FIG. 1; FIG. 9 is a perspective view of a safety selector for AR15 pattern firearms according to a second embodiment of the present design;

FIG. 10 is a 180 degree rotated perspective view of FIG. 9; FIG. 11 is a rear plan view of the design shown in FIG. 9; FIG. 12 is front plan view of the design shown in FIG. 9; FIG. 13 is a right side view of the design shown in FIG. 9; FIG. 14 is a left side view of the design shown in FIG. 9; FIG. 15 is a top view of the design shown in FIG. 9; FIG. 16 is a bottom view of the design shown in FIG. 9; FIG. 17 is a perspective view of a safety selector for AR15 pattern firearms according to a third embodiment of the present design;

FIG. 18 is a 180 degree rotated perspective view of FIG. 17; FIG. 19 is a rear plan view of the design shown in FIG. 17; FIG. 20 is front plan view of the design shown in FIG. 17; FIG. 21 is a right side view of the design shown in FIG. 17; FIG. 22 is a left side view of the design shown in FIG. 17; FIG. 23 is a top view of the design shown in FIG. 17; FIG. 24 is a bottom view of the design shown in FIG. 17; FIG. 25 is a perspective view of a safety selector for AR15 pattern firearms according to a fourth embodiment of the present design;

FIG. 26 is a 180 degree rotated perspective view of FIG. 25; FIG. 27 is a rear plan view of the design shown in FIG. 25; FIG. 28 is front plan view of the design shown in FIG. 25; FIG. 29 is a right side view of the design shown in FIG. 25; FIG. 30 is a left side view of the design shown in FIG. 25;

(Continued)

FIG. 31 is a top view of the design shown in FIG. 25; and, FIG. 32 is a bottom view of the design shown in FIG. 25. The broken lines in the drawings disclose unclaimed portions of the safety selector for AR15 pattern firearms only and form no part of the claimed design.
